UNITED STATES PATENT OFFICE.

LOUIS R. COTY, OF HELENA, MONTANA.

DESIGN FOR A HOUSING FOR HAY-RACK WHEELS.

46,246.

Specification for Design.

Patented Aug. 11, 1914.

Application filed May 27, 1914. Serial No. 841,386. Term of patent 14 years.

To all whom it may concern:

Be it known that I, LOUIS R. COTY, a citizen of the United States, residing at Helena, in the county of Lewis and Clark and State of Montana, have invented a new, original, and ornamental Design for a Housing for Hay-Rack Wheels, of which the following is a specification, reference being had to the accompanying drawing, forming part thereof.

Figure 1 is a side elevation of a housing

for hay rack wheels embodying my design. Fig. 2 is a top plan view of the device. Fig. 3 is an end view thereof.

I claim:

The ornamental design for a housing for hay rack wheels, as shown.

LOUIS R. COTY.

Witnesses:

T. L. PEICE,

J. M. ADAMSON.
